UNITED STATES PATENT OFFICE.

ALTON A. GLADDEN, OF ANNAPOLIS, MARYLAND.

STOVE ATTACHMENT.

1,090,045.

Specification of Letters Patent. Patented Mar. 10, 1914.

Application filed April 13, 1912, Serial No. 690,561. Renewed August 19, 1913. Serial No. 785,595.

To all whom it may concern:

Be it known that I, ALTON A. GLADDEN, a citizen of the United States, residing at Annapolis, in the county of Anne Arundel 5 and State of Maryland, have invented new and useful Improvements in Stove Attachments, of which the following is a specification.

This invention relates to stove attachments.

An object of the invention is to provide 10 an attachment which may be disposed above the burner of the stove so as to effectually protect said burner from overboiling food stuffs.

Another object of the invention is to provide 15 an attachment which is built up of a plurality of separable sections, each having a different transverse diameter so that the 20 device can be made to accommodate a cooking vessel of any desired size.

Another object of the invention is to provide 25 a stove which when combined with the attachment will effectually serve to convey the waste matter to the receiving vat.

A still further object of the invention is 30 to construct the separate sections of the attachment with a view to preventing the accidental lateral separation of the sections when the device is in use.

In the drawing forming a portion of this 35 application and in which like letters of reference indicate similar parts in the several views:—Figure 1 is a top plan view of a stove constructed in accordance with my invention. Fig. 2 is a longitudinal section on line 2—2 of Fig. 1. Fig. 3 is a section on line 3—3 of Fig. 1. Fig. 4 is a perspective view of one of the pot supporting sections.

40 While it is desirable, in view of the purpose of my attachment to combine therewith a particular form of stove wherein the waste material will be arrested and positively held against accumulating immediately around the burner of the stove I do not desire to limit myself in this respect. With a view to obtaining the best results through use of the attachment I have conventionally shown herein a portion of a 45 stove having a top 1 which is provided with one or more top openings 2 which are disposed above the burners 3. The walls 3' of each top opening are flared downwardly and outwardly and they gradually merge into 50 the annular channels or gutters 4 in the top 1.

The channels 4 communicate by way of the branches 5 with a longitudinally extending gutter 6 in the top 1. The gutter 6 preferably inclines slightly toward its discharge end 7 whereby the waste matter or fluids will be made to gravitate to a waste receptacle 8. The receptacle 8 is located beneath the short discharge pipe 9 which extends into the portion 7 of the longitudinal 60 gutter. The channels 4, as described surround the burner openings 2 and in the event of food stuffs overboiling from the utensils while the latter are above the burners of the stove the matter will be conducted 65 into the annular gutters 4 and then finally conveyed to the waste vat 8 as previously described.

The pot supporting attachment 10 comprises one or a plurality of sections 11 which 70 may be built up over each burner opening 2. The sections 11 are substantially of frustoconical form, being open at their upper and lower ends as shown. One section is designed to slightly telescope or fit over the 75 adjacent section and as illustrated each section is of a different diameter and each is provided with a depending flange 12 which is adapted to be extended through the top opening in the section 11 beneath. In this 80 manner all of the sections 11 may be connected together in a manner that will effectually serve to prevent the sections from becoming accidentally disconnected when in use.

90 The sections 11 have their flared walls disposed parallel with the walls 3' of the openings 2 whereby matter overflowing from the boiling receptacle will be conducted by the flared walls of the sections 11 to the 95 gutters 4. By providing sections 11 of different sizes it is evident that the attachment is made to receive or accommodate a cooking vessel of any desired size. It is mentioned that the flared walls of the sections 100 11 serve to concentrate the heat rising from the burners and the application of the heat to the bottoms of the cooking utensils is materially and advantageously increased.

The construction of a stove as described 105 herein, while being extremely simple and inexpensive to manufacture is most useful and desirable in that the clogging of the burner passages of the stove incident to the overflow of matter during the boiling operation is entirely eliminated. With a view 110 to facilitating the handling of the sections

11, each section is provided with a depression or recess 13 which is adapted to receive a suitable stove lifter or the like, not shown.

I claim:—

- 5 1. A stove having its top provided with an annular gutter, the said top having an opening therein, a gutter inclined in the direction of the opening and arranged in open communication with said annular gutter,
- 10 the said top having a pot opening lying wholly within the said annular gutter, and walls defining the said pot opening and inclined in the direction of the annular gutter.
- 15 2. A stove having its top provided with an annular gutter, the said top having an opening therein, a gutter inclined in the direction of the opening and arranged in open communication with said annular gutter,

the said top having a pot opening lying 20 wholly within the said annular gutter, walls defining the said pot opening and inclined in the direction of the annular gutter, and companion interfitting hollow members 25 opened at both ends and disposed above the pot opening and provided with means whereby they are held against lateral displacement from each other and from the opening, each of said members having its inner walls concentrically disposed with relation to the walls of the pot opening.

In testimony whereof I affix my signature in presence of two witnesses.

ALTON A. GLADDEN.
